JAMES D. SMITH, OF NEW YORK, N. Y., ASSIGNOR TO ARTHUR P. EMERY,
OF SAME PLACE.

Letters Patent No. 77,928, dated May 12, 1868.

IMPROVEMENT IN MEASURING-FAUCETS.

The Schedule referred to in these Letters Patent and making part of the same.

TO ALL WHOM IT MAY CONCERN:

Be it known that I, JAMES D. SMITH, of the city, county, and State of New York, have invented a new and useful Improvement in Measuring-Faucets, of which the following is a full, clear, and exact description, reference being had to the accompanying drawing, forming part of this specification, and in which—

Figure 1 represents a side view of a measuring-faucet constructed in accordance with my improvement, the cover to the measuring-chamber being removed.

Figure 2, a top view of the same; and

Figure 3 a view, from the opposite side to that represented in fig. 1, of the gear used to determine and indicate the quantities discharged.

This, my invention, consists in a novel combination, with a measuring-chamber arranged in the head of the faucet, and rotary, draining, and measuring-device located therein, and operated by crank or handle from the outside, of an epicyclic train of wheels of a differential character, and other suitable gear operating in connection therewith, through which motion is communicated by said handle, as it is rotated, to an indicator-dial, preferably hung to revolve by spring or frictional pressure with the gear, so as to be capable of independent adjustment relatively to the pointer.

Referring to the accompanying drawing, A represents the faucet or main body thereof, having arranged between its spigot-end, *a*, and discharge-nozzle *b*, a cylindrical measuring-chamber, *B*, which is in communication, by suitable openings in its periphery, on opposite sides of its axis, with the spigot portion *a* and nozzle *b*, the latter of which may be provided with a gate, *c*, as usual. Within this measuring-chamber is a rotary drawing and measuring-device, *C*, preferably of the character as represented in the accompanying drawing, described in Letters Patent of the United States, No. 70,242, issued to C. Moore and A. P. Emery, October 29, 1867, and wherein *d* is an inner revolving eccentric-cylinder, provided with radial slides, *e*, arranged to clip a loose bolt, *f*, that is concentric to the outer cylinder or chamber *B*, so that on rotating a handle, *G*, fast to the shaft *g* of the eccentric-cylinder *d*, the radial slides *e* operate to draw the fluid through the spigot portion *a* of the faucet, and (the gate *c* being opened) deliver it through the nozzle *b* in measured quantities, corresponding to the capacities of the spaces formed by the radial slides *e* and inner and outer cylinders *d* *B*, whereby, on registering the number of rotations given to the eccentric-cylinder *d*, the total amount discharged is readily ascertainable, or the amount to be delivered fixed by the rotation of the handle any given distance or number of times, an indicator in both cases being used, in connection with the rotating-shaft *g*, to determine and regulate the same.

In such an arrangement of measuring faucet, however, it is highly important not only that the indicator operating in connection therewith should be capable of being readily set or adjusted to register any desired quantity, with facilities for changing the position of the dial relatively to the pointer, or *vice versa*, as new or varied indications are required to be made, but also that the indicator should be capable of registering large as well as small quantities without an objectionable multiplicity of gear connecting the measuring-device with the indicator.

The following combinations of devices serve to secure these ends in a practicable and most efficient manner: Thus, secured to the one side of the measuring-chamber *B*, on its exterior, by boss or projection therefrom, in concentric relationship to the shaft *g*, is a fixed circular rack or wheel, *I*, containing a given number of teeth, while in the same axial line, and lying in close proximity to said rack or wheel, is another and loose or rotating wheel, *J*, of like diameter, containing one or more lesser number of teeth; say, for instance, the stationary wheel or rack *I*, sixty-four teeth, while the movable wheel, *J*, has sixty-three. In gear with this differential arrangement of wheels *I* and *J*, is a pinion, *K*, arranged freely to rotate on or around a pin or stud, *h*, projecting from the handle *G*, so that on rotating the latter to work the drawing and measuring-device *C*, the wheel *J* is moved, say, one tooth every time the pinion *K* travels around the wheels *I* and *J*, whereby a simple and

efficient connection is or may be established with the indicator, capable of registering large quantities without a multiplicity of gearing.

To form the connection with the indicating-dial P: Supposing the dial to move instead of the pointer R, said dial having, as is usual, suitable divisions marked on its face. The wheel J carries or is connected with a bevel-wheel, M, arranged to gear with a bevel-wheel or pinion, N, that operates as the driver to the dial, and whereby a different velocity may be given to the latter, accordingly as the wheels M and N vary in diameter, than that which is attainable from the wheel J direct. This difference may be in favor either of an increased or reduced speed to the dial, but preferably the former, to counteract in a measure the very slow movement of the wheel J relatively to the handle G or its shaft *g*, and measuring-device operated thereby.

The bevel-wheel or pinion N may be fitted to turn loosely on its shaft, *m*, that, being stationary, answers to carry the pointer R and the dial P, also be made to turn freely round the same shaft with a spring, *s*, or springs, interposed between it and the wheel N, and operating to press the dial up or against an outside shoulder to the shaft, by which arrangement the dial, though driven, through frictional pressure of the spring by the wheel N, as required in the action of the indicator, is made capable, by turning it direct, of independent rotation, to vary its set or adjustment relatively to the pointer, accordingly as new or varied indications are required, and whereby the dial may rapidly be brought back to its original position or set for a fresh measurement after a previous quantity has been run off from the faucet, and this without disconnecting parts, or otherwise than applying the hand to the dial to turn it, and without breaking the gear of the latter with its driving-wheel, so that on removing the hand from the dial after adjustment, it is in working connection with the gear operated by the measuring-device.

What is here claimed, and desired to be secured by Letters Patent, is—

1. The combination, with a rotary measuring and drawing-device, C, arranged in the chamber B of the faucet A, and turned from the outside by crank or handle G, of the fast and loose differential wheels I J, pinion K, carried by the handle and wheels M N, or their equivalents, for operating the dial P, substantially as shown and described.
2. The dial P, hung for independent action, as described, and for free rotation with the wheel N, by which it is driven by frictional gear with the latter, through a spring or springs interposed between said wheel and dial, essentially as specified.

JAS. D. SMITH.
